UNITED STATES PATENT OFFICE.

HENRY W. WILSON, OF DULUTH, MINNESOTA.

ROLLING-MILL HOUSING.

Application filed January 28, 1922. Serial No. 532,478.

This invention relates to a new and improved rolling mill construction and more particularly to a rolling mill housing adapted for merchant mills, rod mills and other continuous mills.

In the housings for such rolls, it is necessary to provide for vertical adjustment of the bottom roll, for support of the upper roll, for lateral or axial adjustment of both rolls, and further to provide for an upper bearing for the upper roll and for convenient means for removing the rolls. Common means for vertical adjustment of the bottom roll comprise wedges or jacks operated by means of shafts extending upwardly through the housing. In case of the jack, it is necessary that each side of the housing be adjusted separately. To accomplish this adjustment, it is necessary that the operator go upon both sides of the housing, and to go upon the inside of the mill the operator must climb over and go between the moving parts and the drive gearing, which is quite dangerous. According to my invention, the vertical adjustment of the bottom roll is accomplished by means of completely enclosed jacks which are both operable from the same side of the housing which side is, of course, the outside of the mill.

The general method of supporting the upper roll consists in four hang bolts extending through the housing. These bolts complicate the construction and are difficult in adjustment. Further, the upper bearing for the upper roll usually comprises a casting held in place by two heavy head screws.

In my improved construction the top roll is supported upon an element which is carried upon levers pivoted in the housing. The top bearing consists of a housing cap which is laterally movable into and out of horizontally extending recesses in the housing. This presents a much more easily adjustable construction than the usual one, and one which is composed of but few parts, and which simplifies the necessary castings.

It is necessary to provide lateral or axial adjustment of the rolls. In constructions heretofore in use, it has been necessary to make these adjustments from both the inside and the outside of the mill. According to my invention, these adjustments are both made from the outside of the mill which results in a saving in time and avoids the necessity for the operator climbing over to the dangerous inside of the mill.

It is an object of the present invention to provide a new and improved rolling mill construction comprising a housing having vertical adjustment of the bottom roll entirely operable from the outside of the mill.

It is a further object to provide a construction providing a simple and readily adjustable support for the upper roll.

It is an additional object to provide a housing cap serving as an upper bearing for the upper roll which cap is readily removable and is retained in place without necessity for bolts and nuts.

It is also an object to provide a construction having means for the lateral or axial adjustment of the rolls, this adjustment being accomplished entirely from the outside of the mill.

Other and further objects will appear as the description proceeds.

I have illustrated a preferred embodiment of my invention in the accompanying drawings, in which—

Figure 1 is an end elevation of my improved housing construction;

Figure 2 is a fragmentary side elevation of the housing; and

Figure 3 is a section taken on line 3—3 of Figure 1.

The housing comprises the base portion 7 and the side standards 8 and 9. The lower roll 10 has the roll necks 11 and 12 fitting in the opposite sides of the housing. As shown in Figure 1, the neck 11 rests upon bearing 13 which bearing is supported upon block 14.

The upper roll 15 is provided with roll necks 16 and 17. As shown in Figure 1, the roll neck 16 rests upon block 18 which latter is supported in element 19. The ends of this element 19 are supported upon the inner end of the levers 20, these levers being pivoted at 21 to the standards of the housing. The lug 22 extends laterally from each of the standards above the levers 20 and an adjusting screw 23 is threaded through each lug and bears upon the outer end of the adjacent lever 20.

The bearing 24 rests upon the upper face of the roll neck 16. The housing cap 25 is fitted into the grooves 26 in the two standards, the upper faces 27 of these grooves being inclined downwardly so that upward thrust upon the cap tends to draw the standards together rather than to separate them.

The yoke 28 has the lugs 29 bearing

against the outer face of the bearing block 13. The bolts 30 and 31 extend through the housing standards and are provided at their outer ends with nuts bearing against the yoke 28'. I have shown in Figure 2 a similar yoke 28 provided with lugs 29' bearing against the bearing block 13' which supports the opposite roll neck 12. The long bolts or rods 32 extend across the width 10 of the housing, their inner ends carrying the nuts 33 bearing against the face of the yoke 28' and their outer ends carrying the nuts 34. As clearly shown in the drawings, the upper bearing blocks 24 and 24' are axially adjustable by means of similar bolts and rods.

The lower bearing 13 of the lower roll neck rests upon the block 14 which is elevated by a screw jack indicated in broken lines 20 in Figure 1. Both ends of the lower roll are supported in this manner, and the two screw jacks are operated by the transverse shafts having the squared ends 40 and 43 shown in Figure 1.

25 In the use of my construction, the lower roll may be vertically adjusted by means of the rotation of the two jacks which rotation is accomplished by fitting suitable cranks to the squared portions 40 and 43. 30 This adjustment is carried out entirely from the same side of the housing which side, of course, would be the outside of the mill.

The vertical movement of the upper roll so as to bring its bearing to properly thrust 35 against the housing cap is accomplished by means of the screws 23. Downward movement of these screws moves the outer ends of the levers 20 downwardly, thus lifting the inner ends and consequently lifting the element 19 and with it the roll and its upper bearing.

The housing cap 25 is readily removable by a lateral movement in the recesses 26 sufficient to bring it clear of the recesses.

45 Lateral movement of the bearing members 13 and 13' is accomplished by corresponding lateral adjustment of the yokes which bear against these members. The yoke 28 is ad-

justed by loosening or tightening the nuts upon the bolts 30 and 31. The adjustment of the bearing member 13' is accomplished by moving the yoke 28 through loosening or tightening the nuts 34. While these adjustments only operate to positively move the bearing blocks inwardly, it will be understood that since these blocks bear against the roll adjacent the roll neck, inward movement of one block will accomplish any necessary outward movement of the opposite block when the requisite nuts are loosened to permit such movement.

55 My construction is relatively simple and is adapted to permit rapid adjustment and assembly of the several parts. The vertical adjustment of the lower roll and the lateral 65 adjustment of both rolls are all accomplished from the outside of the mill which results in a considerable saving in time and it avoids the dangerous work upon the inside of the mill. My improved housing cap 70 greatly simplifies the construction and makes it possible to more rapidly remove the rolls when necessary.

The embodiment shown is to be understood as illustrative only as I am aware that 75 various changes and modifications may be made to adapt my construction to varying uses. It is my intention to cover all such modifications coming within the scope of the appended claim.

80 I claim:

A rolling mill construction comprising a housing, a roll having necks supported in the housing, supporting bearings for a roll neck adapted to bear against the roll end to 85 limit its axial movement, a yoke engaging each bearing at one end, the yokes engaging the bearings at points thereof on opposite sides of the axis of the roll neck, and means engaging each end of the yokes for moving 90 the yokes relative to the housing, all said means extending to one side of the housing.

Signed at Duluth, Minnesota, this 20 day of January, 1922.

HENRY W. WILSON.
